UNITED STATES PATENT OFFICE.

GEORGE S. BEST, OF SAN DIEGO, CALIFORNIA.

DOORBELL STRUCTURE.

Application filed November 4, 1925. Serial No. 66,771.

My invention relates to a door-bell structure, and the objects of my invention are: first, to provide a mechanical bell structure of this class which may be mounted on a door, a door casing, on or through a building wall or the like for audibly signaling the occupants of the building, house or room as to the presence of someone outside; second, to provide a bell structure of this class which is provided with a pivotally mounted ringing bell adapted to be positioned on the inside of a room and which is provided on the outside or opposite side of the wall or door of the room with means to indicate a ringing or signaling means on the inside; third, to provide a bell structure of this class having on the inside a pivotally mounted ringing bell and on the outside a dummy bell structure connected with the former and pivotally shiftable therewith, whereby the pivotal shifting of the outer dummy bell will produce an audible gong on the inside; fourth, to provide a bell structure of this class having a shiftable sound producing bell on the inside, a representation of a bell hung from beam supports, the supports connected and shiftable with the bell on the inside, said beam supports being provided with chains or other pulling means at the opposite ends for tilting the supports of the representation of the bell on the outside for ringing the bell on the inside; fifth, to provide as a whole a novelly constructed bell structure of this class, and sixth, to provide a bell structure for doors and walls of rooms, dwellings or other buildings, which is particularly simple and economical of construction, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a fragmentary sectional elevational view of a wall structure taken through the casings surrounding a conventional door opening in a building, with my door-bell structure mounted on the casings of the wall and extending therethrough, the structure shown at the right being posi-

tioned at the outside of the wall and shown partially in section, with the section taken through 1-1 of Fig. 2, the structure on the inside of the wall being also shown partially in section to facilitate the illustration; Fig. 2 is a front elevational view of the bell with a representation of a bell on the inside, with means for oscillating the same, and Fig. 3 is a front or end elevational view of the sound producing bell means on the inside of the wall.

Like characters of reference refer to similar parts and portions throughout the several views of the drawings.

Referring to the drawings, the member 1, adapted to be positioned at the outside of the wall structure, indicated by W, to attract attention to a bell on the inside of the wall structure, consists of a shell 1^a representing a tower or mission bell, which is supported at the lower portion and intermediate the ends of a supporting beam structure 1^b which is also made in the form of a shell, the shell portion 1^a being represented as supported, by means of ropes 1^c, from the supporting beam shell 1^b, all portions of the member 1 being cast as a unitary element. At the back side of the supporting beam structure or shell 1^b is provided a backwardly extending hollow boss 1^d in which is secured, by means of a set screw 2, the one end of an operating rod or spindle 3. This rod or spindle 3 extends transversely through the wall structure and is rotatably mounted at its opposite ends on and through escutcheon plates 4 and 5, respectively secured, by means of screws 6, to the outer and inner faces of the wall structure W, as shown best in Fig. 1. The end of the hollow boss 1^d is preferably abutted against the outer face of the escutcheon plate 4.

The sounding, ringing or signaling bell means at the inside of the room or building consists of a bell member 7 molded of bell material in the shape of a tower or mission bell, and is secured at its upper end to another supporting or beam structure 8, the bell member 7 and the member 8 being also preferably molded as an integral unit. The bell member 7 is also represented as secured, by means of a rope 8^a, over the member 8. The member 8 is tapped as its inner end, as indicated by 8^b, in which is secured the inner, externally threaded end of the rod or spindle 3, as shown best in Fig. 1. The inner end of the member 8, at its tapped por-

tion, is abutted against the bearing face of the escutcheon plate 5.

Within the bell member 7 is secured, by means of an eye bolt or screw 11, the one end of the clapper rod 9, which is provided at its free end with a heavy clapper member 10, made of lead or other suitable material, which is adapted to engage the lower peripheral portion of the bell member 7 when the latter is pivotally shifted about its axis from the outside of the wall, by oscillating the member 1.

At the ends of the supporting beam structure or shell 1^b of the member 1 are secured the one ends of a pair of chains 12 of any suitable length, which extend downwardly from the portion 1^b in a free manner and are provided at their lower ends with knobs 13 or similar members for conveniently pulling the chains 12 at their lower ends for oscillating the member 1 and in turn oscillating the bell member 7 for ringing the same.

Though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In a door-bell structure, a bell member, provided with a clapper, adapted to be pivoted at its upper portion on the inside of a wall, operating means secured thereto and adapted to extend through the wall, means representative of a bell adapted to be positioned at the outside side of the wall and operatively connected with said means for oscillating and ringing said bell member with the oscillation of the means representative of a bell, said last mentioned means being provided with laterally extended portions extending transversely with the pivotal axis thereof, and means secured to and suspended from the ends of said laterally extended portions to facilitate the oscillation of said last mentioned means.

2. In a door-bell structure, the combina-

tion with a wall, of a spindle adapted to be rotatably supported through and transversely with the wall, a tower-type bell secured to the one end of said spindle and provided with a clapper for engaging the shell of said bell when the latter is oscillated, means representative of a bell secured to the opposite end of said spindle to indicate the presence of a signaling means, said means being adapted for oscillating said bell, and means connected to laterally extended portions of said last mentioned means to facilitate the oscillation of said bell.

3. In a door-bell structure, the combination with a wall, of a spindle rotatably supported through and transversely with the wall, an integral bell member consisting of a portion representative of a supporting beam and a bell portion suspended therefrom, the portion representative of the supporting beam structure being screwably secured to the one end of said spindle, a clapper pivotally mounted within said bell portion, and means secured to the opposite end of said spindle for rotating the same and oscillating said bell member.

4. In a door-bell structure, the combination with a wall, of a spindle rotatably supported through and transversely with the wall, an integral bell member consisting of a portion representative of a supporting beam and a bell portion suspended therefrom, the portion representative of the supporting beam structure being screwably secured to the one end of said spindle, a clapper pivotally mounted within said bell portion, means secured to the opposite end of said spindle for rotating the same and oscillating said bell member, said means being molded as an integral shell indicative of a supporting beam structure and a tower-type bell tied thereto and suspended therefrom, and means secured to and suspended from the lateral ends of said last mentioned means at the portion thereof indicative of the supporting beam structure, to facilitate the oscillation thereof for ringing said bell member.

In testimony whereof, I have hereunto set my hand at San Diego, California, this 27th day of October, 1925.

GEORGE S. BEST.
